Inventor
Harry Nielsen,

By *Clarence O'Brien*,
Attorney

UNITED STATES PATENT OFFICE

HARRY NIELSEN, OF ASKOV, MINNESOTA

FENCE POST

Application filed May 14, 1931. Serial No. 537,402.

This invention relates to new and useful improvements in fence posts and has for its primary object to provide, in a manner as hereinafter set forth, a device of this character embodying novel means for securing fence wire thereto in a manner to prevent accidental detachment of the wire from the post but permitting removal of the wire when desired by properly manipulating the securing means.

Other objects of the invention are to provide a fence post of the character described which will be simple in construction, strong, durable, efficient and reliable in use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation showing a portion of a fence post constructed in accordance with this invention.

Figure 2 is a view taken at right angles to Figure 1.

Figure 3 is a view in horizontal cross section taken substantially on the line 3-3 of Figure 1 looking downwardly, as indicated by the arrows.

Figure 4 is a detail view in perspective of the resilient keeper showing the same detached from the post.

Referring now to the drawings in detail, it will be seen that the post is designated generally by the reference numeral 1, an intermediate portion only of said post being shown, the post being substantially T-shaped in horizontal cross section and comprising the integral portions 2 and 3.

At spaced points the portion 2 of the post 45 has formed therein substantially rectangular, vertically extending openings only one of which is shown and designated by the reference numeral 4. The opening 4 communicates, at an intermediate point, 50 with the free edge of the portion 2 of the

post 1 through the medium of a slot or passage 5.

At its lower end the opening 4 is provided with a reduced extension in the form of a slit 6, the outer wall of which constitutes 55 an extension of the outer wall of the opening 4. The extension or slit 6 is for the reception of the lower end portion of a keeper in the form of a resilient, metallic tongue 7 having the integral retaining flanges 8 on 60 its lower end portion for disposition on opposite sides of the portion 2 of the post 1 in a manner to retain the keeper in position. The keeper 7 is normally engaged against the outer wall of the opening 4 and 65 it traverses the slot or passage 5 in a manner to close said slot or passage at its inner end. The free end of the keeper 7 is disposed in spaced relation to the upper end wall of the opening 4. As will be apparent, 70 the purpose of the keeper 7 is to retain the fence wire 9 in the opening 4.

In use, the wire inserted in the opening 4 through the slot or passage 5 by flexing the keeper 7 inwardly and passing the wire 75 over the free end thereof after which said keeper springs back to its operative position against the outer wall of the opening 4, thereby closing the slot or passage 5. It will be noted that the keeper is mounted in 80 position on the fence post without the use of extraneous securing means, such as solder or rivet and without the necessity of welding. This constitutes an important and desirable feature of the invention, as will 85 be readily appreciated.

It is believed that the many advantages of a fence post constructed in accordance with this invention will be readily understood, and although the preferred embodiment of the invention is as illustrated and described, it is to be understood that changes in the details of construction and in the combination and arrangement of parts may be resorted to which will fall within the scope 90 of the invention as claimed.

What is claimed is:

1. A fence post of the character described having an opening therein for the reception of a fence wire and further having a slot 100

therein for the passage of the wire into the opening from one side of the post, said post still further having a slit communicating with the opening, and a keeper mounted on the post for retaining a wire in the opening, said keeper comprising a resilient tongue having an end portion disposed in the slit, and integral flanges on said one end portion of the tongue disposed on opposite sides of the post for retaining the tongue in position.

2. A fence post of the character described having an opening therein for the reception of a fence wire and further having a slot communicating with an intermediate portion of the opening for the passage of the fence wire thereinto from one side of the post, said post still further having a slit therein communicating with the opening at one end and constituting a reduced extension to said opening, and a keeper for retaining the fence wire in the opening, said keeper comprising a resilient tongue extending normally across the inner end of the slot in the opening in a manner to close said slot, one end portion of the tongue being disposed in the slit, and flanges formed integrally with said one end portion of the tongue and disposed on opposite sides of the post for retaining the tongue in position.

3. A fence post of the character described having a substantially rectangular, vertically extending opening therein for the reception of a fence wire, said post further having a transverse slot communicating with the opening at an intermediate point for the passage of the fence wire into said opening from one side of the post, said post still further having a slit therein communicating with one end of the opening and constituting a reduced extension to said opening, and a keeper for retaining the fence wire in the opening, said keeper comprising a resilient tongue having one end inserted in the slit, and retaining flanges formed integrally on said one end of the tongue and extending therefrom adjacent opposite sides of the post for securing the tongue in position thereon, said tongue normally extending over the inner end of the slot in a manner to close said slot and having its free end disposed immediately adjacent the other end of the opening.

4. A fence post of the character described having a substantially rectangular, elongated opening extending vertically therein for the reception of a fence wire, said post further having a transverse slot extending from one side edge and merging with the opening at an intermediate point in said opening for the passage of the wire thereinto from said one side of the post, said post still further having a vertically disposed slit therein communicating with the opening at the lower end of said opening, said slit con-

stituting a reduced extension to the opening and having one wall flush with the wall of the opening which is adjacent said one side of the post, and a keeper for retaining a wire in the opening, said keeper comprising a resilient, metallic tongue having one end portion disposed in the slit, said keeper normally extending in abutting engagement with said one wall of the opening over the inner end of the slot in a manner to close the said slot and having its free end normally disposed immediately adjacent the other end of the opening.

5. A fence post of the character described having a substantially rectangular, elongated opening extending vertically therein for the reception of a fence wire, said post further having a transverse slot extending from one side edge and merging with the opening at an intermediate point in said opening for the passage of the wire thereinto from said one side of the post, said post still further having a vertically disposed slit therein communicating with the opening at the lower end of said opening, said slit constituting a reduced extension to the opening and having one wall flush with the wall of the opening which is adjacent said one side of the post, and a keeper for retaining a wire in the opening, said keeper comprising a resilient, metallic tongue having one end portion disposed in the slit, said keeper normally extending in abutting engagement with said one wall of the opening over the inner end of the slot in a manner to close the said slot and having its free end normally disposed immediately adjacent the other end of the opening; said tongue adapted to be flexed away from said one wall of the opening for the insertion and removal of the fence wire around the free end thereof, and retaining flanges on said one end portion of the tongue extending adjacent opposite sides of the post for retaining the tongue in position.

In testimony whereof I affix my signature.

HARRY NIELSEN.
